(57) **CLAIM**

The ornamental design for a dual grit sharpening stone with gripping band, as shown and described.

DESCRIPTION

FIG. 1 is a perspective view of a dual grit sharpening stone with gripping band illustrating my new design;

FIG. 2 is a front view thereof;

FIG. 3 is a rear view thereof (and a mirror image of FIG. 2);

FIG. 4 is a top view thereof;

FIG. 5 is a bottom view thereof;

FIG. 6 is a left view thereof; and,

FIG. 7 is a right view thereof (and a mirror image of FIG. 6).

1 Claim, 5 Drawing Sheets
